UNITED STATES PATENT OFFICE

2,508,173

WOOL YARN DISPENSING BRACELET

Hyman Kellerman, Brooklyn, N. Y.

Application June 19, 1947, Serial No. 755,579

2 Claims. (Cl. 242—136)

1

This invention relates to a wool yarn dispensing bracelet.

It is an object of the present invention to provide a wool dispensing bracelet which is of light weight which can be disposed on the wrist of the person doing the knitting and which is adapted to carry a ball of wool yarn so that it may be rotated to dispense the yarn as it is being used.

Another object of the present invention is to provide a wool dispensing bracelet which has a protector means for the yarn to keep the same from getting dirty at times when the bracelet is removed from the arm and the same is laid on a table or other surface where there might be dust or dirt and wherein the parts are of such material that they can be cleaned or washed at any time so that the yarn can be disposed on clean parts.

Other objects of the present invention are to provide a wool dispensing bracelet which is of simple construction, inexpensive to manufacture, easy to locate the ball of yarn thereupon and convenient to use.

According to the invention, there is provided a bracelet adapted to be fitted onto the arm of the knitter and from which there extends a pin on which a yarn ball is mounted. A stop plate is provided for mounting on the end of the pin in a manner to retain the ball of yarn in place and to prevent the same from sliding off the end of the pin. The pin may be hinged to the bracelet element so that the yarn can be readily adjusted to the proper and more comfortable position for the knitter.

Also the bracelet may be provided with divided container parts adapted to house the ball of yarn whereby to protect the same from becoming dirty when the bracelet is removed from the wrist and rested upon a surface that may have dust or other dirt thereon. When the knitter is to do the knitting, the bracelet is picked up and readily and easily engaged about the wrist. As the parts thereof are made of light weight material, preferably plastic, the knitter will hardly know that the ball of yarn and the bracelet is being carried by the arm. Means may be provided to limit the pivotal movement of the yarn relative to the bracelet which is engaged about the wrist.

For further comprehension of the invention, and of the objects and advantages thereof, reference will be had to the following description and accompanying drawing and to the appended claims in which the various novel features of the invention are more particularly set forth.

In the accompanying drawing forming a material part of this disclosure:

2

Fig. 1 is a perspective view of one form of the invention including a rigid bracelet part and a pin having a ball and socket connection with the bracelet part adapted to receive the arm.

Fig. 2 is a cross sectional view taken on line 2—2 of Fig. 1.

Fig. 3 is a perspective view of a modified form of the invention wherein the part adapted to fit about the wrist is of different construction than that shown in Fig. 1 and wherein the connection of the pin with the part is different.

Fig. 4 is a cross sectional view taken on line 4—4 of Fig. 3.

Fig. 5 is a perspective view of still another form 15 of the invention in which container parts are hinged to the bracelet or wrist part for concealing the ball of yarn.

Fig. 6 is a cross sectional view taken on line 6—6 of Fig. 5.

Fig. 7 is a fragmentary top plan view of the form of the invention shown in Fig. 5.

Referring now particularly to Figs. 1 and 2, there is shown a rigid wrist part 11 formed of preferably plastic material adapted to be slightly sprung in order that a wrist 12 can be extended through an opening 13 in the wrist part 11. The wrist part 11 is pressed outwardly, as indicated at 14, to provide a socket for receiving a ball formation 15 on a pin 16. With the pin 16 extended through the socket 14, it will be retained against outward movement from the wrist part 11 and at the same time will be permitted some lateral movement. A ball of yarn 17 will be placed upon the pin 16 and its end extended to

35 a knitting needle 18 held in the hand of the arm 12. With the ball of yarn 17 in place, a stop 19 can be extended over a ball formation 21 on the outer end of the pin 16. This stop 19 is in the form of a plate with a hole therein and this hole 40 is of such size that it can be slightly expanded and fitted over the ball end 21.

In Figs. 3 and 4, there is provided a ring 22 having separated ends 23 over which may be extended a sleeve 24 when the ring 22 has been disposed 45 or expanded over the wrist 12. The sleeve is indicated at 24. A separate socket 25 is pivotally connected to the ring 22 and can be adjusted over the same to different positions therealong and over the major portion of the ring but will be 50 retained against displacement from the ring 22 by the ends of the sleeve 24. The socket 25 receives a ball formation on the inner end of a pin 27. On the outer end of the pin 27 is the removable plate 19. This form of the invention is not 55 as rigid as the previous form and may be better suited to some knitters.

Referring now particularly to Figs. 5, 6 and 7, a rigid wrist part 31 is formed with struck out portions 32 adapted to receive a pin 33 for hingedly connecting to the wrist part 31 container parts 34 and 35 and a pin 36 for receiving the ball of yarn and adapted to extend between the parts 34 and 35 to contain the ball of yarn therewithin. The container part 35 will keep the yarn covered and prevent the same from becoming dirty as when the bracelet is laid upon a flat surface or the like which may have dust or other accumulated matter thereupon.

The container 34 has hinge formations 37 thereon for receiving the pin 33. This part 34 also has a hole 38 through which the yarn can be extended. At the opposite end of the part 34 removed from its hinge formation 37 is a catch spring 39 adapted to enter a recess 41 in the container part 35 whereby to retain the parts together. When the parts 34 and 35 are hinged apart, the ball of yarn can be extended over the pointed pin 36. As the parts are brought together, they will surround the ball of yarn and the pin 36.

The part 35 has a hinge formation 42 thereon also adapted to receive the pin 33. The pin 36 has a loop 43. On the container part 35 is a stop member 44 which may limit the amount of pivotal movement of the container parts in one direction upon abutting the wrist part 31.

As shown in Fig. 4, stop plate 47 may be connected to the rod 27 by a threaded connection, as indicated at 48 (Fig. 4).

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A wool dispensing bracelet comprising a wrist part adapted to be fitted about the wrist

of the knitter, a pin extending from the wrist part adapted to receive a ball of yarn, and separable ball container parts adapted to fit about the ball and about the pin respectively pivotally connected to the wrist part, one of said container parts having a stop adapted to bear against the wrist part whereby to limit the movement of the container in one direction relative to the wrist part.

2. A wool dispensing bracelet comprising a 10 wrist part, adapted to be fitted about the wrist of the knitter, a pin extending from the wrist part adapted to receive a ball of yarn, separable ball container parts adapted to fit about the ball and about the pin respectively pivotally connected 15 to the wrist part, said wrist part having projections extending therefrom, said container parts having hinge formations, a pivot pin extending between the projections on the wrist part and through the hinge formations whereby to couple 20 the container parts to the wrist part for pivotal movement relative thereto and relative to each other, said first pin being hinged to the pivot pin and extended into the container for receiving the ball of yarn, and a stop member mounted on one 25 of said container parts for engaging said wrist part to limit pivotal movement of said container parts in one direction toward said wrist part.

HYMAN KELLERMAN.
